CLAIM

The ornamental design for a “inflatable enclosure”, as shown and described.

DESCRIPTION

FIG. 1 is a top perspective view of the inflatable enclosure; FIG. 2 is a front view thereof;

FIG. 3 is a rear view thereof;

FIG. 4 is a top view thereof;

FIG. 5 is a left view thereof; and,

FIG. 6 is a right view thereof.

The broken line shown represent portion of a inflatable enclosure that form no part of the claimed design.
